DESIGN FOR A COMBINED AUTOMOBILE GEAR SHIFT HAND SELECTOR AND HAN- DLE, OR SIMILAR ARTICLE

Ralph F. Peo, Buffalo, N. Y., assignor to Houde
Engineering Corporation, Buffalo, N. Y., a cor-
poration of New York

Application March 30, 1938, Serial No. 76,181

Term of patent 7 years

To all whom it may concern:

Be it known that I, Ralph F. Peo, a citizen of the United States and a resident of the city of Buffalo, in the county of Erie and State of New York, have invented a new, original, and ornamental Design for a Combined Automobile Gear Shift Hand Selector and Handle, or Similar Article, of which the following is a specification, reference being had to the accompanying drawing, forming a part thereof.

On the drawing:

Figure 1 is a perspective view of the combined automobile gear shift hand selector and handle showing my new design; and

Figure 2 is a side elevational view thereof.

I claim:

The ornamental design for a combined automobile gear shift hand selector and handle, or similar article, as shown.
